CLAIM

The ornamental design for a solid back insert for a wheelchair, as shown and described.

DESCRIPTION

FIG. 1 is a front view of a solid back insert for a wheelchair illustrating my design;

FIG. 2 is a side elevational view thereof, the opposite side being a mirror image thereof;

FIG. 3 is a top plan view thereof, the bottom side being a mirror image thereof; and,

FIG. 4 is a rear view thereof.

FIG. 1

FIG. 2

FIG. 3

FIG. 4
